UNITED STATES PATENT OFFICE.

RONALD F. McFEELY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PULLING-OVER MACHINE.

1,356,642.

Specification of Letters Patent.

Patented Oct. 26, 1920.

Application filed February 16, 1917. Serial No. 149,000.

To all whom it may concern:

Be it known that I, RONALD F. McFEELY, a citizen of the United States, residing at Beverly, in the county of Essex and State 5 of Massachusetts, have invented certain Improvements in Pulling-Over Machines, of which the following description, in connection with the accompanying drawings, is a specification, like reference characters on the 10 drawings indicating like parts in the several figures.

This invention relates to machines for use in the manufacture of boots and shoes for pulling the upper over the last, and an object of the invention is to improve the construction of such machines in certain respects relating particularly to the positioning and holding of the upper on the last. An important feature of the invention resides 15 in a novel construction and arrangement of means for positioning a tensioned upper upon a last in preparation for an upper fastening operation. The illustrative construction shown comprises means for 20 clamping the upper against the lateral surface of the last and a wiper carried by the clamping means and movable relatively thereto to wipe the margin of the portion of the upper engaged by the clamping means 25 over the sole or inner sole, hereinafter termed generically the "sole," on the bottom of the last into position for the fastening operation. In accordance with a further feature of the invention, the upper positioning means is 30 supported independently of the upper fastening mechanism, thus permitting this mechanism to perform its function free from any strain incident to the pressure of the shoe on said means. The construction shown 35 provides clamping means for engaging the upper at opposite sides of the shoe adjacent to the bottom edge of the last, and wipers slidably mounted on the clamping means and spring controlled to permit said means to 40 move to clamping position while the upper is held by the grippers in position to oppose inward movement of the wipers, and then to cause the wipers to be forced inward over the margin of the last bottom upon the release 45 of the upper by the grippers.

The above and other features of the invention will be more fully described with reference to the accompanying drawings, which show an illustrative embodiment of

the invention, and will then be pointed out 55 in the claims.

In the drawings,

Figure 1 is a perspective view showing a shoe in its relation to mechanism in which the invention is embodied;

Fig. 2 is a view partly in elevation and partly in section, illustrating by full and dotted lines different positions of the mechanism with relation to an upper under tension;

Fig. 3 is a view in elevation of the mechanism at one side of the shoe, showing the parts as positioned for the tack driving operation, and

Fig. 4 is a perspective view of a portion of 70 the mechanism shown in Fig. 3.

The invention is herein shown in its application to a well known type of pulling-over machine having features of construction such as shown and described in United States Letters Patent No. 1,029,387, granted upon my application on June 11, 1912, and No. 1,135,954, granted upon my application on April 13, 1915, which may be referred to for a more complete understanding of the 75 details of construction and mode of operation of the illustrative machine, only such features as are particularly related to the present invention being shown and described herein in detail.

The machine comprises grippers 2 for engaging and pulling an upper at opposite sides of a last 4, a sole rest 4 for holding the last against the pulling action of the grippers, side arms 6 (herein frequently termed 90 clamp supports) which are moved to carry upper clamping and last supporting member into operative position after the machine has come to rest with the upper under tension, and tacker arms 8 which are moved 95 inwardly over the last bottom into position for driving tacks to fasten the upper in place. Mounted on each of the arms 6 is an upper clamping member 10 comprising a pad positioned to engage the upper at the 100 side of and adjacent to the bottom edge of the last when the arm is moved toward the shoe, to hold the upper in position against the last. Each member 10 is mounted on a clamp holder or carrier 12 which is arranged to slide in a substantially horizontal guideway in the outer end of the arm 6 and has rack teeth in engagement with

a pinion 14 on the arm. Below the pinion is an inclined guideway in which is mounted a slide 16 also provided with rack teeth in engagement with the pinion 14 and carrying at its upper end a last supporting member 18. A spring 20 engaging at one end an abutment plate 22 on the arm 6 is arranged to force the slide 16 downwardly and outwardly and thus to position 5 this slide normally at its limit of downward and outward movement and at the same time through the pinion 14 to position the clamp member 10 at its inner limit of movement relative to the arm 6. Accordingly, 10 when the arms 6 are moved toward the shoe the clamp members 10 engage the shoe before the supporting members 18 engage it, and the latter are then moved up into engagement with the shoe by the action of the 15 pinions 14 in the continued movement of the arms with relation to the members 10. The members 18 are thus brought into position to support the last against the downward pressure of the sole rest 4 when the grippers 20 release the upper and also against the force of the tack drivers. In order to lock each 25 supporting member in operative position a ratchet wheel 24 is mounted to turn with the pinion 14 and a pawl 26 is arranged to 30 engage this wheel and retain it in the position to which it is turned in the upward movement of the slide 16. The construction thus far described may be and is herein shown as substantially identical with that 35 shown and described in the prior Patent No. 1,135,954, hereinbefore mentioned.

In carrying out the objects of this invention, there are mounted on the upper clamping means, comprising the supporting arm 40 6 and the member 10 at each side of the shoe, wipers 28 for the purpose of laying the upper over the margin of the sole and the bottom of the last in position to be tacked. These wipers are carried by holders 29 slideable in a guideway in the clamp holder 12, and springs 32 tensionable in a direction 45 substantially parallel to the direction of the movement of the side clamping means toward the shoe are arranged to position the 50 wipers normally in advance of the clamp member 10, as shown by full lines in Fig. 2. Accordingly, upon the inward movement of the arm 6, the wipers 28 will engage the upper of the shoe before the clamp member 55 10 engages it, and since the upper at this time is held under tension by the grippers 2 in the position shown, the wipers will be restrained from movement to operative position over the last bottom. The arm 6 will 60 continue to move, however, until the members 10 and 18 are both firmly engaged with the upper on the last, such movement of the arm with relation to the wipers serving to compress the springs 32. The parts will 65 then be positioned substantially as indicated

in dotted lines in Fig. 2. As illustrated by this figure, the force of the springs 32 may be such as to bend the upper to some extent between the grippers and the last, thus further tightening the upper on the last. 70

During the final stage of the cycle of operations of the machine inward movement is imparted to the grippers 2 and the tacker arms 8 in the usual manner to overdraw the upper and to position the tackers over the 75 margin of the sole on the bottom of the last, and during such movement the tacker arms finally trip the grippers 2 and cause the latter to release the upper. As the upper is thus overdrawn and finally released the 80 springs 32 force the wipers 28 inward and cause them to wipe the upper over and lay it firmly upon the margin of the sole on the bottom of the last, the wipers co-operating with the clamp members 10 and the shoe 85 supports 18 to retain the tension of the upper in the brief interval between its release by the grippers and the driving of the tacks. The wipers, moreover, are so positioned 90 relatively to the supports 18 that the last is held firmly between the wipers and the supports and the wipers are caused to press the upper firmly on the sole. The continued movement of the tacker arms brings them into tack driving position as shown in Fig. 95 3, such position being determined by the engagement of stops 34 on the arms with abutments 33 on the slides 12. The tacks are then driven, after which the parts of the machine are returned to their initial positions, the pawls 26 being disengaged from the ratchet wheels 24 by the inertia of the pawls when the arms 6 arrive at their limits of outward movement.

The construction shown provides two 105 pairs of gripper jaws at each side of the last, and two wipers 28 and springs 32 also are provided at each side, one for each pair of jaws, the two wipers and their holders 29 being mounted side by side and movable 110 independently of each other on the clamp slide 12 in order to permit them to conform readily to variations in the contour of the last. It will be understood, however, that the invention is not restrictive with respect 115 to the particular number of the wipers or other parts, and moreover that in its broader aspects the invention is not limited to mechanism for operating in any particular position along the margin of the last, the 120 expression "lateral surface" of the last being used herein to distinguish from the bottom and top surfaces without reference to any particular portion of the lateral periphery. 125

Having described the invention, what I claim as new and desire to secure by Letters Patent of the United States is:

1. A machine of the class described having, in combination, means for pulling an 130

upper over a last, upper fastening means, means supported independently of said upper pulling means and fastening means for clamping the pulled upper against the 5 lateral surface of the last close to the edge of the last bottom, and a wiper slidably supported on said clamping means for movement relatively thereto to lay the margin of the portion of the upper engaged 10 by said clamping means over the bottom of the last prior to the fastening operation.

2. A machine of the class described having, in combination, means for pulling an upper over a last, means for clamping the pulled upper against the lateral surface of the last close to the edge of the last bottom, upper fastening means supported independently of said clamping means, a wiper supported by said clamping 15 means for wiping inward the margin of the portion of the upper engaged by the clamping means, and means for moving the wiper relatively to the clamping means to wipe the upper over the feather of the shoe sole on the bottom of the last after the clamping 20 means has engaged the shoe and prior to the fastening operation.

3. A machine of the class described having, in combination, means for pulling an upper over a last, means for clamping the upper against the last while the upper is held by said pulling means comprising a member for engaging the upper at the side of the last adjacent to the edge of the last 35 bottom, a wiper supported on said clamping means and movable relatively thereto, and automatically operative means for moving said wiper inward to lay the margin of the portion of the upper engaged by said member over the bottom of the last after said 40 member has been moved to clamping position.

4. A machine of the class described having, in combination, means for pulling an upper over a last, means for clamping the pulled upper against the lateral surface of the last while the upper is held by the pulling means, a wiper carried by the clamping means for laying the upper over the 45 margin of the bottom of the last in position to be fastened, said wiper and clamping means being relatively movable to permit said means to move to clamping position while the wiper is held back by the tensioned upper, and means arranged to be tensioned by said movement of the clamping means for imparting operative movement to the wiper upon the release of the upper by the pulling 50 means.

5. A machine of the class described having, in combination, means for pulling an upper over a last, means for clamping the pulled upper against the lateral surface of the last while the upper is held by said 55 pulling means, a wiper slidably mounted on

said clamping means for movement to wipe the upper inward over the feather of the sole, said wiper being arranged to operate upon the margin of that portion of the upper which is engaged by said clamping 70 means, and a spring for imparting operative movement to said wiper after the clamping means has moved to clamping position.

6. A machine of the class described having, in combination, means for pulling an upper over a last, means for clamping the pulled upper against the lateral surface of the last while the upper is held by the pulling means, a wiper mounted over the shoe engaging portion of the clamping means and 75 movable relatively thereto to wipe the upper inward over the last bottom, yieldable means for positioning said wiper in advance of the shoe engaging portion of the clamping means as the clamping means moves inward while 80 permitting the clamping means to move relatively to the wiper when the wiper engages the tensioned upper, said positioning means being constructed and arranged to force the wiper over the margin of the last bottom 85 upon the release of the upper by the pulling means.

7. A machine of the class described having, in combination, means for pulling an upper over a last, means for clamping the pulled upper against the lateral surface of the last while the upper is held by the pulling means, a wiper mounted over the shoe engaging portion of the clamping means and 90 movable relatively thereto to wipe the upper inward over the last bottom, and a spring for operating said wiper, said spring being arranged to yield as the clamping means moves to clamping position after the wiper 95 engages the tensioned upper and to move the wiper subsequently to lay the upper over the margin of the last bottom immediately upon the release of the upper by the pulling means.

8. A machine of the class described having, in combination, means for pulling an upper over a last, a clamp support movable toward and from the last, a clamp holder mounted on said support, a clamp member mounted on said holder for engagement with the upper, said support and holder being relatively movable to permit movement of the support toward the shoe after said member engages the upper, and a wiper carried by said holder and movable relatively thereto to wipe the margin of the portion of the upper engaged by said clamp member inward over the last bottom.

9. A machine of the class described having, in combination, means for pulling an upper over a last, a clamp support movable toward and from the last, a clamp holder mounted on said support and movable relatively thereto, a clamp member mounted on said holder for engagement with the 125 upper

upper at the side of the shoe, spring means acting between said holder and support to press the holder inwardly toward the shoe, a wiper carried by said holder for laying the upper over the margin of the last bottom, said wiper being movable relatively to the holder inwardly or outwardly over the shoe, and a spring for positioning said wiper normally in advance of the clamp member while permitting it to yield relatively to said member in response to resistance of the upper.

10. A machine of the class described having, in combination, means for pulling an upper over a last, a clamp support movable toward and from the side of the last, a clamp holder slidably mounted on said support for movement toward or from the shoe, an upper engaging clamp member on said holder, spring means for pressing said holder inwardly toward the shoe, a wiper slidably mounted on said holder, and a spring for pressing said wiper inwardly over the shoe.

11. A machine of the class described having, in combination, means for pulling an upper over a last, a clamp support movable toward and from the last, a clamp holder slidably mounted on said support for movement toward or from the shoe, a clamp member on said holder for engagement with the upper, and a wiper slidably mounted on said holder for movement in the same direction as the holder to lay the upper over the margin of the bottom of the last.

12. A machine of the class described having, in combination, means for pulling an upper over a last, shoe holding means comprising a clamp member for engaging the upper at the side of the last and a last supporting member, said holding means being constructed and arranged to cause the last supporting member to be moved to supporting position by engagement of the shoe with the side engaging member, means for locking said supporting member in supporting position, a wiper carried by said shoe holding means for laying the upper over the margin of the last bottom, said wiper and holding means being relatively movable to permit said means to move to holding position when movement of the wiper is stopped by engagement with the tensioned upper, and means for forcing the wiper over the last bottom when the upper is released by the pulling means.

13. A machine of the class described having, in combination, grippers for pulling an upper over a last at opposite sides, means for clamping the pulled upper against the sides of the last close to the edge of the last bottom, means for tacking the upper, and wipers slidably mounted on the clamping means for wiping the upper over the feather of the sole of the shoe after the upper has been clamped and prior to the operation of the tacking means, said wipers being limited

to engagement with portions of the upper at a distance from the toe end of the shoe.

14. A machine of the class described having, in combination, grippers for pulling an upper over a last at its opposite sides, clamping means movable into position to clamp the upper against the sides of the last while the upper is held by the grippers, wipers mounted on the clamping means, said wipers and the clamping means being relatively movable to permit said means to complete its movement after the movement of the wipers is stopped by engagement with the tensioned upper, and springs for holding said wipers in engagement with the upper while the upper is held by the grippers and for operating the wipers to lay the upper over the margin of the last bottom immediately upon the release of the upper by the grippers.

15. A machine of the class described having, in combination, grippers for pulling an upper over a last at its opposite sides, said grippers being limited to engagement with portions of the upper at a distance from the toe end of the shoe, clamping means movable into position to engage the upper at opposite sides of the shoe adjacent to the bottom edge of the last, wipers slidably mounted on the clamping means for movement to lay the margin of the portion of the upper engaged by said clamping means over the bottom of the last after the clamping means has moved to clamping position, said wipers being arranged to operate upon substantially the portions of the upper engaged by said grippers, and tacking instrumentalities supported independently of the clamping means and the wipers and movable inwardly over the last bottom into position for driving tacks to fasten the upper.

16. A machine of the class described having, in combination, grippers for pulling an upper over a last at its opposite sides, means for clamping the pulled upper against the sides of the last, wipers slidably mounted on the clamping means, means for operating said wipers to lay the upper over the bottom of the last after the clamping means has moved to clamping position, tacker arms movable inwardly over the last bottom into position to fasten the upper, and means carried by said clamping means for limiting the inward movement of the tacker arms.

17. A machine of the class described having, in combination, a gripper for engaging an upper on a last, means for effecting relative movement of said gripper and the last to pull the upper, clamping means movable into engagement with the upper on the lateral surface of the last close to the edge of the last bottom while the upper is held by said gripper, a support on which said clamping means is mounted, a member also carried by said support for laying the mar-

gin of the portion of the upper engaged by said clamping means over the sole of the shoe on the bottom of the last, and spring means for positioning said member relatively to the clamping means, said spring means being arranged to yield to the pressure of the tensioned upper on said member as the clamping means moves to clamping position and to move said member inward 10 over the sole of the shoe immediately upon release of the upper by the gripper.

18. In a machine of the class described, the combination with means for pulling an upper over a last, of a clamping device 15 movable toward the shoe into position to clamp the tensioned upper against the lateral surface of the last, a wiper member mounted over the shoe engaging portion of the clamping device and movable with said 20 device toward the shoe, and a spring for positioning said member normally with its shoe engaging portion in advance of the shoe engaging portion of the clamping device, said spring being arranged to yield 25 upon engagement of said member with the tensioned upper to permit the clamping device to move relatively to said member and to operate the member to wipe the margin of the upper over the feather of the sole 30 when the upper is released by the pulling means.

19. In a machine of the class described, the combination with means for pulling an upper over a last, of a clamping device movable toward the shoe into position to clamp the tensioned upper against the lateral surface of the last, a wiper member for engaging the margin of the portion of the upper engaged by said device, said member being 35 movable with said device toward the shoe and movable also relatively to said device in the same direction, and a spring for positioning said wiper member relatively to the clamping device, said spring being tensionable in a direction substantially parallel 40 to the direction of the movement of said

device toward the shoe and arranged to permit said member to yield upon engagement with the tensioned upper and subsequently to operate said member to wipe the margin 50 of the upper over the sole of the shoe.

20. In a machine of the class described, the combination with means for pulling an upper over a last, of a wiper support movable toward the shoe while the upper is 55 under tension, a wiper carried by said support and movable relatively to the support in directions toward or from the shoe, a spring for positioning said wiper relatively to the support, said spring being arranged 60 to yield to the pressure of the tensioned upper on said wiper and to operate said wiper subsequently to wipe the margin of the upper over the sole of the shoe, and tacking means mounted independently of 65 said wiper support and movable across the same portion of the edge of the shoe bottom as said wiper into position to drive tacks for holding the margin of the upper in place. 70

21. In a machine of the class described, the combination with means for pulling an upper over a last, of a support movable toward and from the side of the shoe, a device carried by said support for engaging the 75 tensioned upper to clamp it against the lateral surface of the last, said device being spring controlled to permit the support to continue its movement toward the shoe after the device engages the shoe, and a wiper 80 member carried by said clamping device and also spring controlled to permit it to yield relatively to said device laterally of the shoe against the resistance of the tensioned upper, said wiper member being constructed and arranged to wipe the margin 85 of the upper inward over the sole of the shoe when the upper is released by the pulling means.

In testimony whereof I have signed my 90 name to this specification.

RONALD F. McFEELY.
